FAN AND METHOD OF ASSEMBLY AND DISASSEMBLY

Murray S. Kice, Jr., Detroit, Mich., assignor to
American Blower Corporation, Detroit, Mich.,
a corporation of Delaware

Application May 20, 1946, Serial No. 671,022

3 Claims. (Cl. 230—134)

1

This invention relates to fans and blowers and particularly to fans of the Sirocco type and to methods of repairing the same.

The Sirocco type fan or blower is one in which the fan wheel comprises a plurality of circumferentially spaced and axially extending blades which transfer gas between an axial inlet opening in a fan housing to a peripheral outlet opening. This type of fan is characterized by blades which are relatively narrow in the radial direction but of which there are a multiplicity spaced around the periphery of the fan rotor. The result of this blade arrangement is a highly efficient fan, especially well adapted to induced draft installations and which operates at relatively low speeds, and with little noise.

The construction of this type fan produces a relatively low moment of inertia, which, together with the low operating speed, results in correspondingly low stresses in the fan parts during operation. This type fan has the further advantage of being relatively insensitive to vibration from conditions of slight out of balance which would be serious in blowers of other types.

Accordingly, the primary object of the present invention is to provide an improved method for repairing the fan wheels of fans and blowers, especially of the Sirocco type.

Another object is to provide an improved type fan wheel for a Sirocco type fan which is so arranged that replacement of the fan wheel when it is desired to repair a blower is facilitated.

Still another object is to provide a Sirocco fan wheel and a method of assembling and disassembling same such that a fan or blower can be repaired in the field without dismantling the heavy drive shaft from the fan housing.

These and other objects and advantages will become more apparent upon reference to the following specification taken together with the accompanying drawings in which:

Figure 1 is a perspective view of an induced draft fan having a fan wheel therein according to this invention;

Figure 2 is a fragmentary perspective view of the fan wheel of Figure 1 showing the arrangement thereof more in detail;

Figure 3 is a cross section through a fan wheel constructed according to this invention and is indicated by the line 3—3 on Figure 4;

Figure 4 is a cross section indicated by the line 4—4 on Figure 3;

Figure 5 is an enlarged view indicated by the line 5—5 on Figure 3;

2

Figure 6 illustrates the manner of severing the rim of the fan wheel during disassembly; and

Figures 7 and 8 show how the fan wheel rim may be scarfed and welded when the fan wheel is reassembled.

General arrangement

According to the present invention a fan or blower is provided which has a portion of the casing thereof removable so that access can be had to the fan wheel. The removable portion of the casing is easily removed from the fan, or may be hinged so that it can be latched in an open position. The removable or hinged section of the casing is independent of the bearings which support the fan wheel shaft so that the casing may be readily opened at any time.

According to the present invention, it is proposed that the fan wheel within the fan be so constructed that it can be removed for replacement or repaired without removing the fan wheel shaft. This is accomplished by constructing the fan wheel from spaced end rings or rims with the blades supported therebetween and securing one of the said rings to a hub plate which is carried on the fan wheel shaft. Then, by detaching the blades and rings from the aforementioned hub plate, the fan wheel proper may be split by cutting through the end rings at diametrically opposite points and the resulting halves of the wheel removed from the casing.

It will be apparent that this method of removing the fan wheel from the fan or blower is substantially quicker and more easily accomplished than previous methods wherein the fan wheel and fan wheel shaft were removed in their entirety from the fan casing and the wheel removed from the shaft by sliding it axially over the end of the shaft.

The fan is reassembled on the shaft in the same manner that it was disassembled by inserting the fan halves into the casing, securing them to the fan hub plate and welding the halves together along their line of separation at both places on both of the end rings. The assembled fan is then balanced, if necessary, and the unit is again ready for operation.

It will be apparent from the foregoing that this invention provides for a very rapid and simple means of effecting repairs to blowers without the necessity of removing the fan wheel shaft from the fan casing, and that the efficiency of the fan unit is substantially unimpaired by the operator.

3
Structural arrangement

Referring more particularly to the drawings, there is illustrated a fan having a casing 10 which may comprise a pair of inlet openings at 12 which communicate with the fan rotor 14 from the opposite ends thereof. The fan rotor 14 is adapted for discharging gas peripherally into a central scroll passage 16 in the fan casing which communicates with a discharge conduit at 18. The fan wheel 14 is carried on a fan wheel shaft 20 which is journaled in the bearing blocks 22 at each end of the fan.

For facilitating the inspection and repair of the fan wheel, the fan casing 10 comprises a portion 24 which is removable from the casing or which may be hinged thereto for being raised to the position shown in Figure 1.

The fan wheel with which this invention is concerned is better illustrated in Figures 2, 3 and 4. In these views it will be seen that each side of the double inlet fan wheel 14 is comprised of a pair of end rings or rims 26 and 28 between which there are supported a plurality of blades 30. For securing the fan wheels on the fan wheel shaft 20, the latter mounts a hub 32 and a hub plate 34. The hub plate 34 has substantially the same diameter as the rims 26 and 28 and is apertured to receive mounting bolts which also pass through the rims 28. In general, four bolts as indicated at 36 will be sufficient to secure the fan wheels to the hub plate 34, but it will be understood that any number desired may be employed. The plate 34 may be bolted, riveted or welded to the hub 32, and preferably one of the last two means is employed.

Inasmuch as the blades 30 are relatively closely spaced, it may be necessary to delete one of the blades at each mounting bolt in order to accommodate the said bolt but the efficiency of the fan is substantially unimpaired by this omission of blades.

The blades may be secured between the rings in any suitable manner, such as by riveting, and if riveted, at least the rivets passing through the rims 28 are required to have counter-sunk heads as indicated at 38 in Figure 5. This enables the rims 28 to fit closely against the hub plate 34 so that the maximum amount of support is given the fan wheels to insure greater rigidity and freedom from vibration.

Returning to Figures 1 and 2, should it become necessary to repair or replace one or both of the portions of the fan wheel 14, this may be accomplished by unbolting the said portions from the hub plate 34, cutting them in half by splitting the rims 26 and 28, and removing the resulting halves from the fan casing.

Since any wear on the wheel due to abrasion thereof by particles carried in the gas stream occurs at the heel of the blades 30 at the center of the wheel, or opposite the hub 32, the removed shells can be reversed and replaced. In this case the rims may be split in any convenient place but it is preferred that they be split along diametrically opposite lines and between a pair of adjacent blades, substantially midway between two of the attaching bolts 36. By dividing the wheel into substantially identical halves the balancing of the wheel, upon re-assembly, is facilitated because no great amount of unbalance results from the welding necessary during the re-assembly.

In this case of re-using the present wheel, the rims are scarfed after being torched through. The outer rim 26 is scarfed as indicated in Figure 75

7, as re-assembly welding can be done on both sides. The center rims 28 are scarfed as shown in Figure 8, to afford all welding being done from one side.

In the case of the installation of new wheel parts on the present hub plate 34, the halves of the portion or portions are placed within the fan casing and bolted in place on the hub plate 34. The wheel halves are then bolted, centered, and welded, the scarfing of the rims having been done at the factory. Preferably, the outer rim 26 is scarfed and welded on both sides as indicated at 40 in Figure 7 while the inside rims 28 are scarfed and welded only on the side opposite the plate 34 as is indicated at 42 in Figure 8. The line along which the rims are split is substantially radial but may be somewhat inclined in order to accommodate for the position occupied by the blades 30. A representative cutting line is indicated at 44 in Figure 6.

After the new or repaired wheel halves have been rewelded and secured to the back plate 34, it is preferable that the fan rotor be balanced, if necessary, by welding weights around the periphery of the wheels. This is preferably accomplished by arc welding weights on the outside of the outside portion.

While this invention has been shown and described in connection with a double inlet type fan, it will be obvious that it is equally well adapted to fans of the single inlet type wherein it is inconvenient to remove the fan wheel in its entirety from the fan wheel shaft.

It will be apparent that the Sirocco type fan is particularly well adapted for being dismantled and reassembled according to this invention. This is due to the fact that the Sirocco fan wheels operate at substantially lower speeds than other type fan wheels, have considerably smaller dead weight and have the parts thereof under considerably lower stresses during operation. Accordingly, this type of fan wheel can be manufactured from a mild and easily welded steel rather than from a special alloy steel and hence, can be welded without the weakening thereof at any part. However, it will be understood that in many instances other types of fan wheels can advantageously be repaired in the field by practicing the methods of the present invention.

It will be understood that this invention is susceptible to modification in order to adopt it to different usages and conditions and, accordingly, it is desired to comprehend such modifications within this invention as may fall within the scope of the appended claims.

I claim:

1. A fan wheel consisting of, a pair of annular ring end rims, and a plurality of blades extending between said rims disposed axially thereof and fixedly connected thereto, each of said blades having a foot at each end thereof fixedly connecting the said blades to the said rims, the said blades being positioned equidistantly from each other substantially by the said feet thereof in a regular occurring sequence, said sequence of said blades being broken at periodic intervals equidistantly positioned about said rims with a space occasioned by omission of a blade from the regular sequence thereof between adjacent blades substantially greater than the space between the blades in the regular sequence thereof, and means in each rim of the pair in the said greater space for receiving an attaching means whereby to mount said wheel on a support.

2. In a fan, a drive shaft, a hub on said shaft

rotatable thereby, a radially extending flange carried by said hub, a fan wheel unit positioned on said flange, said fan wheel unit consisting of a pair of like individual fan wheels one of which is positioned at each side of said hub, each of said fan wheels consisting of a pair of annular ring end rims, and a plurality of blades extending between said rims disposed axially thereof and fixedly connected thereto, said blades of each of said wheels being positioned equidistantly from each other in a regular occurring sequence, said sequence of said blades in each of said wheels being broken at periodic intervals equidistantly positioned about said rims with a space between adjacent blades substantially greater than the space between the blades in the regular sequence thereof, said fan wheels positioned at each side of said flange each having one open end whereby each of said wheels receives air axially thereof and discharges air radially through said blades, and attaching means extending through said flange and one of said pairs of rims positioned against said flange in the rim portion thereof in the said greater space to detachably attach said wheels to said flange.

3. A method of disassembling and reassembling for reuse a fan wheel unit from a shaft supporting the same without disturbing the position of the shaft, which unit consists of a pair of connected like cooperating individual fan wheels each consisting of a pair of unitary annular ring end rims connected by a plurality of blades extending therebetween and positioned axially thereof in which air moves into the individual wheels axially thereof and discharges therefrom radially through the blades which results in greater wear on the blades at the end portions

remote from the inlet side of the wheels, the said fan wheels being detachably connected together and to a hub mounting carried on the shaft by one of the rims of each of the fan wheels, which consists of, severing each of the unitary end rims of the wheels in at least two places spaced apart a distance greater than the diameter of the shaft that supports the wheels to divide said wheels into independent sectors, detaching the wheel sectors from the hub mounting and removing the sectors from around the supporting shaft, reassembling the cooperating sectors of each wheel around the shaft with the wheels formed thereby in reverse order of their initial position on the shaft whereby the worn portions of the blades are positioned at the inlet side of the wheels, detachably mounting the sectors on the hub mounting, and reuniting the rims into unitary annular rings.
